Earl Trinkle, Youngstown, Ohio, assignor to The Dog House, Inc., Youngstown, Ohio, a corporation of Ohio

Application November 14, 1952, Serial No. 22,298

Term of patent 14 years

(Cl. D13—1)

To all whom it may concern:

Be it known that I, Earl Trinkle, a citizen of the United States, residing at Youngstown, in the county of Mahoning and State of Ohio, have invented a new, original, and ornamental Design for a Store Front, of which the following is a specification, reference being had to the accompanying drawing, forming a part thereof.

I claim:

The ornamental design for a store front, as shown.

EARL TRINKLE.
